United States Patent Office

Des. 232,353

Patented Aug. 13, 1974

232,353

TREAD PLATE MATERIAL OR THE LIKE

Benjamin Sieradzki, Berkeley, Calif., assignor to
Chemetron Corporation, Chicago, Ill.

Filed Nov. 17, 1971, Ser. No. 199,832

Term of patent 14 years

Int. Cl. D25—01

U.S. Cl. D13—1 J

FIG. 1 is a top plan view of a representative portion of tread plate material or the like showing my new design, the balance of the material being like that shown;

FIG. 2 is an elevational view thereof; and

FIG. 3 is a bottom plan view thereof.

I claim:

The ornamental design for tread plate material or the like, as shown and described.
